CABLE CONNECTOR FOR SAFETY BELTS

Clarence W. Rose, 2700 W. Barberry Place,
Denver, Colo.

Filed Dec. 18, 1956, Ser. No. 629,044

10 Claims. (Cl. 24—134)

This invention relates to connectors and attachment devices for ropes, and more particularly to that class of connectors for attaching a rope or cord to a suspended rope or cable, hereinafter referred to as a cable, a main object of the invention being to provide a novel and improved cable-connector for attaching the end of a rope to a suspended cable, usually vertical. As such, the invention is a development from and improvement over my copending application, filed January 10, 1955, Serial No. 480,840, now Patent No. 2,914,139.

The primary purpose of the invention is to provide a novel and improved cable connector for attaching the end of a safety rope or lifeline of a worker's safety belt to and at any selected point along the span of a suspended cable. Such cables may be a part of or may be supplied incident to many types of structures including derricks, elevator shafts, and bridges. Often a worker has to be positioned upon a hazardous perch at a location where an anchor hook or beam is not conveniently available for conventional attachment of a safety rope or lifeline, and it follows that a cable, suspended or hanging from a point above, may be actually the most satisfactory anchor for the attachment of the lifeline of the worker's safety belt. Such a cable may be a permanent part of the structure, or may be supplied for the particular purpose of holding the lifeline.

As set forth in my prior application, that invention was conceived and developed to provide an effective and efficient connector to eliminate the problems incident to the attachment of the lifeline of a safety belt to a suspended cable, and comprises, in essence, a clamp-like connector which is attached to the end of a safety belt lifeline and is adapted to embrace and be locked upon a vertical cable to secure the line to the cable. The present invention is an improved cable connector which includes special means for positive and secure attachment of the connector at any selected position on the cable to prevent inadvertent disengagement or loosening and slipping down of the connector from such desired position, all as hereinafter described in detail.

It follows that general objects of the invention are to provide a novel and improved cable connector for attaching a lifeline to a suspended cable which is quickly and easily secured to or removed from the cable; is adapted to be clamped to the cable at any selected position and to be shifted along the cable to any other position whenever desired; resiliently grips the cable when force is applied to the lifeline and tightens such grip as the force is increased to prevent slipping; is adapted, however, to slide responsive to a predetermined load in decelerating the fall of a wearer and thereby ease the stopping shock to him; is of such construction that a unit may be designed to permit any selected degree of sliding; operates as an effective shock absorber; and is a simple, economical, compact, rugged and reliable safety device.

Further specific objects of the improved invention are to provide a novel and improved cable connector for

2

attaching a lifeline to a vertically suspended cable which is adapted to be positively clamped and locked to a cable at any selected point on the cable by a simple tug of the lifeline and permits the lifeline to be subsequently slackened without danger of releasing the connector from the cable; incorporates simplified automatic cable locking and unlocking means in the elements comprising the connector; renders the connector a reliable safety device by preventing any accidental loosening and slipping of the connector on the cable and insures a positive grabbing of the cable by the connector whenever it is necessary to check the fall of a wearer.

With the foregoing and other objects in view, all of which more fully hereinafter appear, my invention comprises certain novel and improved constructions, combinations and arrangements of parts and elements as hereinafter described, and as defined in the appended claims, and illustrated in preferred embodiment in the accompanying drawing in which:

Figure 1 is a perspective view of a portion of a vertically suspended cable with the improved cable connector mounted thereon and with the associated portion of a twisted rope lifeline engaged to the connector and locking it upon the cable, and with broken lines indicating the manner in which the connector deflects to clamp onto the cable when a load is placed on the lifeline and other broken lines indicating lifeline locking elements in open position.

Figure 2 is an elevational face view of the connector as taken from the indicated arrow 2 at Fig. 1.

Figure 3 is an elevational section as taken from the indicated line 3—3 at Fig. 1.

Figure 4 is a fragmentary sectional detail of the lifeline locking elements as taken substantially from the indicated line 4—4 at Fig. 2 but on an enlarged scale.

Figure 5 is a fragmentary sectional detail as taken from the indicated line 5—5 at Fig. 4.

Figure 6 is a fragmentary sectional detail similar to Fig. 4 but illustrating the elements in position for releasing the lifeline.

Figure 7 is a fragmentary sectional detail similar to Fig. 5 but illustrating the elements in position for releasing the lifeline.

Figure 8 is a fragmentary sectional detail as taken from the indicated line 8—8 at Fig. 2 but on an enlarged scale.

Figure 9 is an elevational side view of the apparatus as being held and spread by an operator as when releasing the apparatus from the suspended cable.

Figure 10 is a perspective view similar to Fig. 1 but illustrating a modified embodiment of the connector as being adapted for use with a smooth-type lifeline, such as a small steel cable.

Figure 11 is a fragmentary detail of a face portion of the connector as taken from the indicated arrow 11 at Fig. 10, but on an enlarged scale.

Figure 12 is a fragmentary sectional detail as taken from the indicated line 12—12 at Fig. 11.

Referring more particularly to the drawing, and to Figs. 1 through 8, the improved cable connector 10 is attached to the end of a lifeline 11 of a safety belt and is adapted to be locked upon a suspended cable 12 to anchor the lifeline to the cable. The lifeline 11 is a selected rope such as nylon or manila formed by conventionally laying three twisted strands together. The cable 12 may be of any conventional type such as manila, hemp, or wire rope, and may be limp, taut, or even a rigid solid bar or pipe. While the cable 12 is illustrated as being circular in section, it is to be understood that it may be of any section which is substantially circular, such, for example, as the section formed by a 7-strand rope. Moreover it is to be understood that the connector

may be adapted for use with non-circular elements such as a rail or rectangular bar.

The connector 10 is formed by two rectangular plates of stiff resilient material such as spring steel, including a carrier plate 13 and a squeeze plate 14 which are hingedly connected at their top edges 15 as hereinafter described. From the interconnected edges 15, these plates are preformed to diverge outwardly so that their respective base edges 16 and 17 are normally spread apart.

Each plate 13 and 14 is formed with a central slot at the top edge 15 which fairs into a vertically aligned tapering trough 18 at the bottom of the slot. Each trough 18 is in spaced opposition with the trough 18 of its mating plate and the troughs and slots thereby form a vertical centered passageway between the plates through which the cable 12 extends. It follows that a hinging action of the plates by moving their lower edges 16 and 17 together will squeeze upon the cable 12 embraced between the plates to effect an engagement and gripping of the connector to the cable.

To accomplish this pulling together of the lower edges of the plates and the gripping of the cable, the lifeline 11 is slippably threaded through orifices in the lower portions of the plates and between the plates whereby a pull of the line brings the plates together. The orifices in the carrier plate 13 include an anchor orifice 19 substantially above the base edge 16 and a threading orifice 20 immediately above the base edge. The orifices in the squeeze plate 14 include a turning orifice 21 at a position preferably slightly lower than orifice 19 when the plates are interlocked in spaced opposition and a second turning orifice 22 immediately above the lower edge 17 and substantially opposite the orifice 20.

The lifeline 11 is threaded through these orifices with its end being tied into a crown knot 23, or similar knot or enlargement and abutting against the anchor orifice 19 and with a soft washer 24 at the orifice to prevent the metal edges of the orifice from abusing the cords forming the knot. Thence, the lifeline 11 extends through this orifice 19 as a connective reach 11a across the gap between the plates, through and about turning orifices 21 and 22, and again as a connective reach 11b across the gap between the plates and through threading orifice 20 to hang from the base edge 16 of plate 13. The opposite end of the lifeline, not shown, will be attached to a safety belt or carry a connector. The path for the lifeline 11 about and through the orifices is suitably smoothed for easy movement of the line through the orifices, as, for example, by bulging or rounding the portion of the plate 14 between the orifices as at 22a and by a similar bulge or rounding of the lower part of the plate 13 as at 20a.

It follows that with a pull of the safety rope 11, the rope will slip through the orifices to shorten the reaches 11a and 11b to thereby draw the base edges of the plates together and squeeze the cable 12 between the troughs 18 of the two plates.

Where a load such as the weight of a man is placed upon the lifeline it is contemplated that the plates will actually give and deflect as from the full-line position illustrated at Fig. 1 and that both plates will deflect to and even beyond the deflected position of the squeeze plate 14 indicated in broken lines. In the ultimate, the base edges of the plates will be pulled together with the portion of the cable 12 below the trough 18 being pushed to one side of the connector by the rounded base edges of the plates. It is anticipated that such will occur when the body of a worker is hanging from the safety line and beneath the connector.

The tightness of the squeeze of the plates 13 and 14 upon the cable 12 will depend upon the shape and size of the plates, and the connector may be designed to lock upon the cable in checking a fall of the wearer of the safety belt whose lifeline is secured to the connector, or preferably, it may be designed to permit a certain prede-

termined amount of sliding so that the fall of a wearer is decelerated to a gradual easy stop. The necessary proportions of the plates for such purposes may be ascertained experimentally by one skilled in the art.

In preferred construction, the hinged interconnection at the top edge is adapted for separation of the plates, and as illustrated, the hinge is formed of rollably inter meshing fingers turned to cylindrical form from the upper edges of the respective plates, the fingers 25 on the carrier plate 13 rollably embracing fingers 26 on the squeeze plate 14 which lie on a common axis when intermeshed. The cylindrical shaped fingers 25 and 26 are not completely turned to fold against their respective plates but provide gaps which permit interconnection and disengaging of the plates 13 and 14 when they are spread approximately 180 degrees apart, as in the manner illustrated at Fig. 9, thus easily permitting engagement with and disengagement from the cable.

When these plates are interconnected and mounted upon the cable 12, they necessarily diverge from the hinged top edge 15 to separate the base edges 16 and 17 until the connector is clamped onto the cable by pulling the base edges together as with the lifeline 11. This normal divergence is suitably supplemented by a bend 27 in the squeeze plate.

When a worker uses this connector as by attaching it to a cable alongside his platform or scaffold it is ordinarily placed on the cable at a height sufficient to give the worker freedom of movement yet minimize the distance he would fall before the lifeline would become taut to check his fall. It becomes essential that the connector remain on the cable at such selected position and not slip or work its way down the cable to a point where the lifeline would interfere with the movements of the worker, possibly trip him and also cause him to fall an unnecessary great distance before the fall is checked. It is also essential that the connector be properly engaged on the cable so that a pull on the lifeline will immediately slip the reaches 11a and 11b to clamp the connector to the cable 12 and not permit the connector to slip down the cable an indefinite distance before it grabs hold of the cable.

Ordinarily, the weight of a lifeline hanging from the orifice 20 is sufficient to provide tension on the reaches 11a and 11b to hold the connector in position on a vertically suspended cable; however, continual movements of the lifeline on the cable by a worker might effect a slackening of the lifeline and the consequent spreading and slipping of the connector down the cable. The present invention, therefore, includes a lock 28 at the threading orifice 20 to permit the reaches 11a and 11b of the lifeline to be held under moderate constant tension in a manner which secures the connector onto the cable and prevents any undesirable or accidental slackening of the lifeline on the connector or other unexpected incident from causing the connector to open and to slip down the cable.

The lock 28 is adapted to permit the lifeline 11 to be freely payed out through the threading orifice 20 to shorten the reaches 11a and 11b and pull together the base edges 13 and 14 of the plates but to prevent reversal of movement of the lifeline without positive release of the lock.

The lock 28 is formed by a rod 29 which is carried at the inner side of the carrier plate 13. Its upper end 30 is affixed to the upper portion of the carrier plate. The end 30 is formed as a threaded stub turned substantially at a right angle. This stub extends through an orifice 31 in the carrier plate and is secured tightly onto the plate by a washer 32 and nut 33 or by riveting or other means of fastening. The rod extends downwardly from this connection to the base of the carrier plate and there turns into and through a slot 34 near the base edge 16 alongside the threading orifice 20.

This turned portion thereby extends through the slot 34 to the outer side of the plate 13 to form the lock 28

proper. The end of the rod at this turned portion turns upon itself in an approximate 180 degree bend to form a finger 35 which extends sidewardly and into the orifice 20 to lie upon the lifeline 11 passing through the orifice.

While the rod 29 lies against the inner side of the carrier plate at its point of connection, at the orifice 31, it extends off and from this surface so that the lower portion of the rod lies spaced a short distance from the carrier plate inner side. This rod is so bent and is naturally tensioned to pull away from the surface of the plate in a manner which tends to forcibly pull the finger 35 into the orifice to bear against the lifeline therein with a moderate pressure.

The lifeline 11 is a conventional twisted rope with the strands 36 laid together in a helical pattern having helical valleys between the strands. The finger 35 is shaped to conform with this helical pattern and to lie in a valley between strands 36 when it moves into the orifice 20. It is tilted slightly so that it is adapted to push the lifeline against and upon the bulge 20a and thereby effectively lock the lifeline against inward movement through the orifice 20, for such movement would tend to pull the hook further into the orifice, and press the lifeline tightly against the bottom of the orifice, upon bulge 20a as clearly illustrated at Fig. 5.

The tension of the rod 29, which normally pulls the hook into the orifice to bear upon the lifeline 11, as illustrated at Figs. 4 and 5, effectively locks the lifeline against movement into the orifice 20a to prevent a spreading apart of the plates 13 and 14 as by an increase of the span of the portions 11a and 11b of the lifeline 11 and consequently, prevents a loosening of the connector on the cable 12. However, this locking may be released by an opposite pull of the lifeline out of the orifice 20 to shorten the spans 11a and 11b and to thereby tighten the connector onto the cable 12, as in the case of arresting a fall of a workman.

This locking may also be released manually as when the finger 35 is pushed out of the orifice and lifted from the lifeline as by thumb pressure pushing the rod 29 against the inward side of the carrier plate 13, as in the manner clearly illustrated in broken lines at Fig. 1. This operation of releasing the lock as by thumb pressure against rod 29 is substantially automatic and without any special manual reflexes because this pressure on the rod 29 normally results whenever a worker grasps the plates to pull them apart and release the connector from the cable 12. He will almost naturally grasp the rod 29 by his thumb or other digit and whenever he attempts to pull the plates apart the natural pressure against the rod 29 functions to release the lock 28.

The alternate construction illustrated at Figs. 10, 11, and 12 contemplates the use of a smooth surface, cylindrical lifeline 11' which may be a circular woven cord or a single strand of twisted wires or the like, such lifeline 11' having no characteristic valleys between twisted strands as does the rope hereinbefore described. With a smooth surfaced, cylindrical lifeline 11', the hook 35 would be ineffectual to lock the lifeline in the orifice 20 of the construction hereinbefore described. The lifeline 11' in that situation would simply slip in the larger orifice 20 whenever an attempt was made to hold it.

To adapt a modified connector 10' for this smooth type lifeline 11', the carrier plate and squeeze plate may be substantially the same as that hereinbefore described. They will be hinged at their upper edges with trough 18 forming a cable receiving passageway and with the lifeline receiving orifices near their lower edge. The lifeline 11' is formed with an enlarged head 23' to hold it at the anchor orifice 19. Thence, the lifeline extends from the carrier plate to the squeeze plate 13 and through the turning orifices 21 and 22 of that plate and then extends through the threading orifice 20' the same as hereinbefore described.

However, the threading orifice 20' is made narrower 75

and is slotted in form to restrict the lateral movement of the lifeline 11' and to provide space above the line to receive a pressure finger 35' for locking the lifeline in position in the orifice. This finger 35' is formed as a bent end of the rod 29' and it extends directly through the orifice 20' and eliminates the slot 34 hereinbefore described. The rod 29' is still formed to resiliently pull the finger through the orifice 20' and the finger 35' is accordingly flattened and flared at its end with the flared end 40 being slightly wider than the orifice 20' to prevent the finger 35' from accidentally slipping through the orifice 20'.

The bottom of the finger is flattened as at 41 to solidly bear against the lifeline 11' while the angle of the bend of the rod 29', to form the finger, is less than 90 degrees to permit the flat underside 41' to lie against the lifeline in the orifice on a slope with respect to the axis of the orifice 20' to effectively push the lifeline against the bulge 20a' at the bottom of the orifice and thereby assure locking of the line therein.

As in the aforescribed construction, the locking action is effective in one direction only and is effective to hold the lower edges of the plates together by not permitting an increase in the lifeline spans 11a' and 11b' and separation of the lower edges of the plates once the connector

25 is properly mounted upon a cable. The connector plates may be spread apart by grasping the rod 29' at the same time the plates are grasped to automatically release the finger 35' in the same manner as hereinbefore described.

While I have described my connector in considerable detail, it is obvious that others skilled in the art may design and build other alternate and equivalent constructions which are within the spirit and scope of the invention; hence, it is my desire that my protection be limited, not by the constructions illustrated and described, but only by the proper scope of the appended claims.

I claim:

1. In a braking clamp for attachment to a vertically suspended cable or the like, including two flat spring plates hingedly connected together at one end and with the other end of each plate being normally separated from the other end of the other plate, clamping means between the plates near the hinged end thereof for holding and clamping upon the cable, the separated end of one plate having an orifice, connecting means in the separated end of the other plate, a pull line slippably threaded through the orifice and connected to the connecting means to span the separated ends of the plates and pull them together for gripping the cable responsive to an outward pull of the line through the threading orifice and resilient directional locking means mounted upon said orifice plate including a resilient rod at the inner face of the orifice plate which extends through the orifice as an inclined finger adapted to bear against the line and jam it against the edge portion of the orifice substantially at the outer face of the plate, said rod being tensioned to hold the finger against the line with resilient pressure and spaced from the inner face of the plate to permit movement of the finger out of the orifice by pressing the rod against the plates as when the plates and rod are manually gripped in a manner as for pulling them apart.

2. In a braking clamp for attachment to a vertically suspended cable or the like, including two flat spring plates hingedly connected together at one end and with the other end of each plate being normally separated from the other end of the other plate, clamping means between the plates near the hinged end thereof for holding and clamping upon the cable, the separated end of one plate having an orifice, connecting means in the separated end of the other plate, a pull line slippably threaded through the orifice and connected to the connecting means to span the separated ends of the plates and pull them together for gripping the cable responsive to an outward pull of the line through the threading orifice and resilient directional locking means mounted

upon said orifice plate including a resilient rod at the inner face of the orifice plate which extends through the plate to the outer face thereof and turns into the orifice as an inclined finger portion adapted to bear against the lifeline and jam it against an edge portion of the orifice substantially at the outer face of the plate, said rod being tensioned to hold the finger against the lifeline with resilient pressure and spaced from the plate to permit movement of the finger out of the orifice by pressing the rod against the plate.

3. In the organization defined in claim 2, said line being a rope of twisted strands and said finger being inclined and curved to extend into the orifice and to normally lie against the line in a valley between the strand twists.

4. In the organization defined in claim 2, wherein the outer edge portion of the orifice against which the line is pressed is rounded to permit smooth movement of the line through the orifice when the plates are being clamped together.

5. A braking clamp adapted to hold the end of a safety belt lifeline on a vertically suspended cable and including in combination, two plates connected together at one end by a hinge with the ends opposite the hinge end of the plates being normally separated, a passage through the hinge through which the cable passes with a gripping surface on each plate adjacent the hinge to grip the cable when the separated ends are pulled together, one plate including a threading orifice at its separated end and the other plate including a connecting means at its separated end whereby an end of a lifeline is slidably threaded into said orifice and connected to said connecting means to span the separated ends of the plates and pull them together responsive to a pull of the lifeline out of the threading orifice, an inclined locking-finger extending into the orifice adapted to bear against the lifeline and lockably jamb it against an edge portion of the orifice wall substantially at the outer side of the plate from whence the lifeline extends and inwardly directed resilient means adapted to hold the locking-finger against the lifeline but to permit the lifeline to pull the finger outwardly from the orifice against the resilient means when the lifeline is being pulled outwardly to pull the ends of the plates together.

6. In the organization defined in claim 5, said inwardly directed resilient means including a resilient rod at the inner face of the plate having an orifice which extends through the plate to the outer face thereof and turns into the orifice as an inclined finger adapted to bear against the lifeline and jam it against the edge portion of the orifice substantially at the outer face of the plate, said rod being tensioned to hold the finger against the lifeline with resilient pressure and spaced from the plate to permit movement of the finger out of the orifice by pressing the rod against the plate.

7. The braking clamp defined in claim 5, wherein said lifeline is a rope of twisted strands and said locking finger extending into the orifice and being adapted to bear against the lifeline is adapted to match the strand twist of the lifeline and thereby lie in a valley between the strand twists when contacting the lifeline.

8. A safety clamp adapted to hold the end of safety belt lifeline on a vertically suspended cable, and including, in combination therewith, two flat plates connected

together at one end by a hinge, a passage through the hinge through which the cable passes with a gripping surface in each plate adjacent to the hinge adapted to grip the cable when the plates are pulled together at an acute angle with the ends opposite the hinge end being normally separated, the separated end of one plate having a threading orifice, connecting means in the separated end of the other plate whereby said lifeline is adapted to be threaded into the orifice and extended to said connecting means to span the separated ends to pull them together responsive to a pull of the lifeline out of the threading orifice to impose gripping pressure onto the cable at said gripping surfaces, and resiliently operative directional locking means extending through said orifice adapted to permit the lifeline to be pulled through the orifice to pull the ends of the plates together but to lock the lifeline against opposite movement into the orifice and thereby prevent separation of the plates when the tension on the lifeline is relaxed, and wherein said lifeline is a rope of twisted strands and said locking means includes a resilient rod at the inner face of the orifice plate which extends through the plate to the outer face thereof and turns into the orifice as a curved, inclined finger adapted to lie upon the lifeline in a valley between strand twists and jamb it against the orifice wall, said rod being tensioned to hold the finger against the lifeline with resilient pressure and being spaced from the plate to permit movement of the finger out of the orifice by pressing the rod against the plate.

9. The braking clamp defined in claim 5, wherein said lifeline is a smooth surfaced rope, and wherein said orifice is formed as a slot having a width substantially that of the lifeline diameter with the lifeline lying at one side of the slot and with said locking finger being adapted to lockably jamb the lifeline against the edge portion of the orifice at said side of the slot.

10. The braking clamp defined in claim 5 wherein said lifeline is a smooth surfaced rope, wherein said orifice is formed as a slot having a width substantially that of the lifeline diameter with the lifeline lying at one side of the slot and with said locking finger being adapted to lockably jamb the lifeline against the edge portion of the orifice at said side of the slot, and wherein said inwardly directed resilient means includes a resilient rod at the inner face of the orifice with said finger being attached to an end of the rod.
